UNITED STATES PATENT OFFICE

2,518,584

CENTRIFUGAL SWITCH

Calvin J. Werner, Dayton, Ohio, assignor to General Motors Corporation, Detroit, Mich., a corporation of Delaware

Application January 19, 1945; Serial No. 573,486

5 Claims. (Cl. 200—80)

1

This invention relates to improvements in control devices and particularly such devices which are operated by a centrifugal actuator.

It is among the objects of the present invention to provide a centrifugally actuated control device which operates quietly and over a long period of time without replacement of parts rendered inoperative due to excessive wear.

A further object of the present invention is to provide the surface of one metallic member of a mechanism with a glazed, vitreous surface material which provides a smooth and substantially non-abrasive surface over the comparatively rougher surface of the metallic member thereby substantially reducing wear of a fibrous part of the mechanism which constantly engages said glazed surface with a revolving movement.

Further objects and advantages of the present invention will be apparent from the following description, reference being had to the accompanying drawings wherein a preferred embodiment of the present invention is clearly shown.

In the drawings:

Fig. 1 is a fragmentary sectional view of an electric motor equipped with the present invention.

Fig. 2 is a view similar to Fig. 1, certain portions of the mechanism being shown in a different position, however.

Fig. 3 is a view taken along the line 3—3 of Fig. 1.

Fig. 4 is a fragmentary, greatly enlarged section of two engaging parts of the mechanism.

Fig. 5 is a view similar to Fig. 4, the one part of the mechanism being shown provided with the present invention.

The switch of the present invention is identical to the one forming the subject matter of the Patent 2,182,977 issued to applicant on December 12, 1939 and filed October 23, 1936, excepting, however, that in the present invention the skillet-shaped lever member 43 is covered with a glazed, vitreous material presenting a smooth and substantially non-abrasive surface upon which the fibrous rubbing member 32 constantly rides.

Referring to the drawings the numeral 20 designates the field frame of a motor equipped with the present invention. A stator comprising a frame 21 and windings 22 and 23 is carried in frame 20. An end cover 24 is secured to the frame 20, said end member rotatably supporting, in a manner not shown, the armature shaft 25 which supports the rotor 26 of the motor.

The shaft 25 has a transverse opening 27 through its axis in which a rod 28 of the centrifu-

2

gal device is slidably supported. A collar 29 is secured to the rod 28 and is normally held in engagement with the shaft 25 by a coil spring 33 which surrounds the rod 28 on the side of shaft 25 opposite the collar 29. Spring 33 is interposed between the shaft 25 and an adjustable nut 34 threaded on one end of the rod 28. A fibrous rubbing collar 32 having a metallic washer of smaller diameter than said collar attached on each side thereof, is mounted on the rod 28 adjacent the collar 29 and several weight members 31 in the form of thick washers are secured on rod 28 and clamped upon the rubbing collar 32 by the head 30 formed at the end of rod 28 opposite the nut 34.

While the shaft 25 is rotating below predetermined speed the spring 33 maintains the rod 28 in the position in which its collar 29 is held upon the shaft 25. However, when the speed of shaft 25 reaches and exceeds this predetermined speed the weight collars 31 will, due to centrifugal force, move outwardly, thus sliding the rod 28 and its rubbing collar 32 and abutment collar 29 outwardly, away from shaft 25 against the effect of spring 33. Fig. 1 shows the centrifugal mechanism in the normal position as the shaft rotates below a predetermined speed and Fig. 2 shows the mechanism in the shifted position responsive to the rotation of shaft 25 at or in excess of the said predetermined speed.

The switch, actuated by the movement of the rod assembly just described comprises an insulating plate 36 secured to the end cover 24 of the electric motor by studs 37 and 38. Stud 37 has a flanged insulator 37a secured thereto inside the end cover 24 and likewise stud 38 has a flanged insulator 38a attached thereto. Two stationary contacts 39 and 40 are carried by the plate 36.

The movable member of the switch comprises a skillet-shaped lever plate 43 having openings for receiving the insulators 37a and 38a respectively. A clearance between each insulator 37a and 38a and its respective opening in the plate 43 is provided so as to permit tilting of the plate. Contacts 41 and 42 are carried by the plate and are adapted to cooperate with the stationary contacts 39 and 40 respectively to make and break electric circuits. A spring 48 surrounds the insulator 37a and is interposed between the outer flange 37b thereof and the adjacent lever portion. This spring exerts a pressure upon the one end of the lever or plate 43 so that, as shown in Fig. 2, it will pivot about its contact 41 resting upon the stationary contact 39 whereby the plate

contact 42 is held out of engagement with its stationary contact 49 and the end of the plate opposite the portion thereof engaged by the spring 48 is urged toward and against the rubbing collar 32.

The end of the skillet-shaped plate 43 adjacent the rubbing collar 32 is frusto-conical in shape presenting a sloping surface 45 and a flat surface 46. The surface 46 has an opening 47 greater in diameter than shaft 25 which extends therethrough, thereby permitting free tilting movement of the plate.

When the electric motor is inoperative, or until it reaches a predetermined operating speed, spring 33 will urge the rod 28 to hold its collar 29 upon shaft 25. Under this condition, as shown in Fig. 1, the rubbing block 32 engages the flat surface 46 of the skillet-shaped plate 43, thus urging said plate counterclockwise about the insulating plate and stationary contacts 42 and 49 respectively, acting as pivot. The spring 48 is compressed under these conditions.

When the electric motor reaches the predetermined speed the rod 28 will be moved by weights 31 in response to centrifugal force. As the rod 28 moves so the rubbing collar 32 thereon moves and as said collar 32 moves away from shaft 25 its rubbing contact will move from the flat 46 along the sloping surface 45 toward its large diameter portion thereby permitting a tilting of the skillet-shaped plate 43 clockwise by spring 48 first about the pivot formed by engaging contacts 42-49 then when contacts 41-39 engage, contacts 42-49 will separate and continued tilting clockwise will be effected about the pivot formed by the non-engaging contacts 41-39.

It will be seen that the dish-shaped end or more specifically the flat or the sloping surfaces of said plate 43 is held in constant engagement with the rubbing block or collar 32. While the motor operates said collar is revolved by the rotating shaft 25, thus the rubbing collar in operation engages the plate 43 in a circular rubbing path.

The skillet-shaped plate 43 is stamped and formed from sheet metal, the surface of which though apparently smooth, presents a microscopically rough and abrasive surface which tests have shown prematurely wears out the fibrous rubbing collar 32 due to its constant rubbing contact with such surface. To avoid this, plates 43 were electroplated as shown in Fig. 4, which is a fragmentary section, on an enlarged scale, of a portion of the plate 43. This figure shows the plated surface covering 50 assuming practically the same contours of the various irregularities in the surface of the plate and this also presents an abrasive surface which will also cause excessive wear upon the engaging fibrous rubbing collar.

Fig. 5 illustrates a fragment of plate 43 at an enlarged scale, treated according to the present invention. Here the surface of the metal making up the plate has the same irregularities as that shown in Fig. 4. Plating of the surface as shown in Fig. 4 does not eliminate these regularities for the plate-deposit is comparatively thin and follows the contours of the irregularities thus still presenting high and low spots which when engaged by the fibrous rubbing collar causes excessive wear thereof. However, when the metal plate 43 is covered with a glazed, vitreous surface such as porcelain 51 or the like, the flow, as the covering is applied, fills all of the irregu-

larities and presents a smooth glass-like outer surface which may be slightly wavy but still avoids the presence of the abrasive irregularities as is the case in the electro-plating of the plate 43. The porcelain 51, flowed onto the plate 43 before subjected to the baking process, fills the recesses 52 in the metal surface, the high spots 53 having a very thin covering of the porcelain. In its fluid state as applied, the porcelain forms a smooth, non-abrasive and glass-like surface which does not cause excessive wear on the constantly engaging rubbing collar 32. In fact tests have proven that a porcelainized plate 43 greatly reduced friction and will cause the rubbing block used with it to far outlast a rubbing block used on a plain or electroplated plate 43. This eliminates replacements and reduces wear of important control parts of the electric motor thereby increasing its efficiency and life.

While the embodiment of the present invention as herein disclosed, constitutes a preferred form, it is to be understood that other forms might be adopted, all coming within the scope of the claims which follow.

What is claimed is as follows:

1. A control device comprising in combination, a stationary element; a movable member shiftable relatively to said stationary element; an actuator member, constantly engaging the movable member and operative to shift said movable member; means urging the movable member into uninterrupted engagement with the actuator and at a substantially unvarying pressure; a fibrous rubbing block attached to one of said members and constantly engaging the other of said members; a hard and smooth vitreous surface covering on the member constantly engaged by the rubbing block, said surface covering being free from abrasive action on said rubbing block; and means for operating the actuator member.

2. A device in accordance with claim 1, in which the rubbing block is attached to the actuator member and in which the portion of the movable member, constantly engaged by the rubbing block, is provided with a hard and smooth porcelain covering having high wear resisting qualities and which is free from abrasive action on said rubbing block.

3. A centrifugal control device comprising in combination, a control member movable from one position into another to effect control; a spring exerting a substantially unvarying pressure upon the control member constantly urging said control member toward one of its control positions; a rotatable member; an actuator on the rotatable member, constantly engaging the control member and normally urging said control member toward the other of its control positions against the effect of the spring; and a hard and smooth vitreous covering on the control member, said covering providing a wear resisting surface, free from abrasive action upon the actuator which constantly engages it.

4. A centrifugal control device comprising in combination, a control member tiltable into two separate control positions, said member having a frusto-conically shaped portion; a spring exerting a substantially unvarying pressure upon the control member constantly urging said member toward one of its control positions; a rotatable member; a centrifugal actuator carried by the rotatable member, said actuator having a fibrous rubbing element in constant engagement with the sloping surface of the frusto-conically shaped portion of said control member and operative to

urge said member toward the other of its control positions against the effect of the spring; and a wear resisting coating of hard, smooth vitreous material on the frusto-conically shaped portion of the control member, said surface being free from abrasive action upon the rubbing element and having a high wear resisting quality which permits an increased spring pressure to be applied to said control member for effecting more efficient control.

5. A centrifugal control device comprising in combination, a metallic member tiltable from one position into another to effect control, said member having a glazed; vitreous coating providing a wear resisting, smooth surface substantially free from abrasive action upon cooperating parts; a centrifugal actuator having a rubbing block in constant engagement with the glazed surface of

said member and operative to effect tilting thereof in response to variations in the rotating speed of the actuator; a spring engaging said member and urging it with a substantially unvarying pressure into constant engagement with said rubbing block; and rotatable means supporting said actuator.
